UNITED STATES PATENT OFFICE

WILLIAM K. ECKHARD, OF DUNELLEN, NEW JERSEY, ASSIGNOR TO R. HOE & CO., INC., OF NEW YORK, N. Y., A CORPORATION OF NEW YORK

PRINTING MACHINE

Application filed October 9, 1929. Serial No. 398,510.

This invention relates to power driven machines used for printing from plates in which the form to be printed is engraved or otherwise depressed below the surface thereof. 5 During the operation of the machine, the plate is covered with ink which is pressed into the engraved part of the plate, and the ink on the surface is then wiped off leaving the ink that is to be transferred to the sheet, in 10 the engraved parts.

The customary method of wiping the surface of the plate by means of a web of fabric involves the waste of considerable ink. This waste is avoided by the ink salvaging mechanism disclosed herein, whereby the excess ink is removed from the surface of the plate by a cleaning roller that transfers it to a salvaging roller from which it is removed by a salvaging blade and returned to the ink fountain. 15

The object of the invention is to provide a practical means for inking an intaglio printing plate, removing excess ink from the surface of the plate, and returning it to the ink fountain. 20

It is also an object of the invention to provide a plate inking and ink salvaging mechanism of generally improved construction, whereby the mechanism will be simple, durable and inexpensive in construction, as well as convenient, practical, serviceable and efficient in its use. 25

With the foregoing and other objects in view, which will appear as the description proceeds, the invention resides in the combination of parts, and in the details of construction hereinafter described and claimed, it being understood that various changes in the 30 precise embodiment of the invention herein disclosed may be made within the scope of what is claimed without departing from the spirit of the invention.

In the accompanying drawings:

45 Figure 1 is a sectional view of the ink fountain of a machine used for printing from intaglio plates, showing certain of the coating rollers and other mechanism in outline.

50 Figure 2 is a fragmentary view partly in section, similar to a portion of Figure 1, but

showing certain of the parts in a different relation; and

Figure 3 is a fragmentary plan view of the mechanism shown in Figure 2 as viewed in the direction of arrow 3 of Figure 2. 55

Referring to the drawings, a portion of the frame of the machine is shown and indicated at 11. It will be understood that suitable bearings for the various rollers are provided in the frame. A portion of the platen is 60 shown at 12, and a printing plate 13 is fastened thereto by suitable means.

The ink fountain, indicated generally at 14, is provided with a fountain roller 15, that is driven by gears 16 and 17 from a convenient rotating shaft of the machine. 65

An ink roller 17 having a covering that may be formed of a suitable resilient moulded composition material, engages the fountain roller 15 and the plate 13. It will be 70 understood that the platen is arranged to slide horizontally from left to right on suitable rails or ways not shown, that support the platen at the height required to bring the plate into engagement with the inking roller. 75

"Rolling in" rollers 18 and 19 engage the plate after it receives ink from the ink roller 17 and serve to distribute the ink and press it into the design that is engraved or etched in the plate. 80

Further motion of the platen brings the plate into engagement with the cleaning roller 21 which is driven by the gears 22 and 23 from a suitable rotating member of the machine. 85

The cleaning roller 21 is preferably made with a moulded composition covering and when it engages the plate it removes the greater part of the ink from the surface thereof. 90

As the roller 21 revolves, the portion that has received ink from the plate comes in contact with the salvaging roller 24 and the ink is deposited thereon.

The ink fountain 14 is provided with the usual fountain blade 25 and adjusting screws, one of which is shown at 26. By these means the feed of ink to the plate is regulated. 95

A chute or fountain extension 27 is provided with clamps, one of which is shown at 28, 100

and thereby adjustably fastened to the brackets 29, secured to the ink fountain. In practice, the extension is preferably adjusted quite close to the salvaging roller, but at a distance sufficient to allow the ink on the roller to pass under it.

A means for removing the ink from the salvaging roller is provided by the blade 31, which is shown in Figure 1 in engagement 10 with the salvaging roller 24. As the salvaging roller is rotated, due to its frictional contact with the cleaning roller 21, the ink is scraped from its surface by the blade and runs down the inclined surface of the fountain extension or chute 27, and is thus returned to the fountain.

The scraper blade 31 is secured to arms 32 that are suitably fastened to the shaft 33. Brackets 34 secured to the ink fountain 14 20 provide bearings for the shaft 33, and an arm 35 that is secured to the shaft is pivotally connected to a rod 36 which slides in a poppet 37 secured to the ink fountain. It will be seen that the spring 38 acting on the collar 39 secured to the rod 36 will press the blade 31 against the salvaging roller.

An arm 41 is also secured to the shaft 33 and is pivotally connected to a rod 42. The lower end of this rod carries a forked member 43 which engages a shaft 44 carrying a cam 45 that is engaged by the roller 46. The shaft 44 is driven in properly timed relation with the movement of the platen and acts to move the blade 28 away from the salvaging 30 roller 24 after it has removed the ink therefrom. The cam 43 is preferably arranged to allow the blade to engage the salvaging roller shortly after the plate engages the cleaning roller, and after the rollers have made 35 a few revolutions the blade is held out of engagement until the next inking operation.

While it is not necessary to lift the blade from the salvaging roller it has been found that by doing so, considerable wear of the 40 parts is avoided.

The ink salvaging mechanism herein disclosed effects a saving in the quantity of ink used, and by removing the greater part of the ink that is on the surface of the plate, 45 leaves less ink to be removed by the wiping mechanism, which in consequence can be used for a longer period before it must be renewed.

What I claim is:

1. In a machine for printing from an intaglio plate, a roller for removing excess ink from the plate and depositing it on a salvaging roller, an ink fountain, a member closely adjacent the periphery of the salvaging roller and extending over the fountain, and 50 means acting intermittently to remove ink from the salvaging roller and deposit it on said member.

2. In a machine for printing from an intaglio plate, means for removing excess ink 55 from the plate and depositing it on a salvag-

ing roller, an ink fountain, a member adjacent to the periphery of the salvaging roller and extending over the fountain, a blade engaging the salvaging roller to remove ink therefrom and deposit it on said member, and means for moving the blade out of engagement with the salvaging roller. 70

3. In a machine for printing from an intaglio plate, a member for removing excess ink from the plate and depositing it on a 75 salvaging member, an ink fountain, a member adjacent to the salvaging member and extending over the fountain and means acting intermittently to remove ink from the salvaging member and deposit it on the said 80 adjacent member.

4. In a machine for printing from an intaglio plate, an ink fountain, means for conveying ink from the fountain and depositing it on the plate, a cleaning roller for removing excess ink from the plate, a salvaging roller on which the ink is deposited by the cleaning roller, a swinging blade adapted to bear against the salvaging roller to remove the ink therefrom, means to move the blade 90 into and out of engagement with the salvaging roller, and a chute adjacent to the line of engagement of the blade with the salvaging roller; said chute being adapted to receive ink flowing from the blade and conduct 95 it to the fountain.

5. In a machine for printing from an intaglio plate, an ink fountain, means for conveying ink from the fountain and depositing it on the plate, a cleaning roller for removing excess ink from the plate, a rotating salvaging roller on which the ink is deposited by the cleaning roller, a blade having its lower edge in engagement with the periphery of the salvaging roller on its upwardly moving side, and a chute having its upper side adjacent to the salvaging roller and to the lower edge of the blade and adapted to receive the ink directly from the edge of the blade and return it to the fountain. 100

In testimony whereof, I affix my signature.
WILLIAM K. ECKHARD.
